Chester N. O'Connell
ATTORNEY

UNITED STATES PATENT OFFICE

FRANK J. CURRAN, OF NEW YORK, N. Y., ASSIGNOR, BY MESNE ASSIGNMENTS, TO STEAM POWER, INC., A CORPORATION OF DELAWARE

SELF CLEANING ATOMIZING NOZZLE

Application filed January 6, 1926. Serial No. 79,581.

This invention relates to atomizers for fluids. More particularly, the invention relates to atomizing means for liquids under pressure for use in oil furnaces and the like.

5 The invention relates further to mechanism for maintaining the nozzle in atomizing devices, clean and free from obstructing deposits.

Generally speaking, the invention consists 10 in the provision of an atomizer having the general formation of a tube in which there is positioned at one end a plurality of ducts, the passageway or communication from the interior of the tube being periodically obstructed by the rotation of a cylindrical member within the tube, said cylindrical member having a plurality of spiral grooves on its surface, whereby rotation is imparted to said cylindrical member by the movement of fluid 15 along said grooves. The invention also contemplates the utilization of an auxiliary mixing chamber exterior to the end passageways, and a single aperture nozzle communicating with said passage.

20 An important object of the invention therefore is the provision, in an atomizer, of a cylindrical member which is rotated by the movement of fluids through the atomizer and which, by its rotation, periodically interrupts the movement of the fluid to the atomizer and thereby serves to break up the fluid and separate the same into minute particles. Another object of the invention is to provide means in a rotatable member positioned within a tubular casing, having a plurality of displaced ducts in one end of the casing which serve to maintain the passage of said ducts clear, and thus maintain the efficiency of the atomizing apparatus. Other 25 objects of the invention are contemplated in the provision of plural atomizing or mixing agencies in a single apparatus, said agencies having different modes of securing the breaking up of the fluid; in means for varying the volume of atomized fluids emitted by said atomizer, and in the provision of means for automatically adjusting for wear in a rotatable member within the atomizer casing. Various other objects will become apparent 30 in consideration of the following specifica-

tion, bringing out details of construction and methods of manufacture, and on inspection of the accompanying drawing, in which:

Fig. 1 is a longitudinal section of the atomizer showing the rotatable member and the 55 nozzle construction;

Fig. 2 is an end view showing the nozzle of the atomizer;

Fig. 3 is a section taken on line 3—3 of 60 Fig. 1;

Fig. 4 is a detailed view of the notched end of the spiral grooves of the rotatable member;

Fig. 5 is an end view of the casing illustrating the ducts therein; and 65

Fig. 6 is a side view of the closed end of the atomizer partly in sections showing the ducts or passageways for the fluid.

Referring more particularly to Figure 1 of the drawing, there is shown, by way of example, an atomizing unit which may be useful as atomizing means for heavy hydrocarbons in household heating furnaces or analogous uses. The atomizer unit 10 is attached to a supporting plate 11 by interengaging threads formed on the surface of the casing 12 of the atomizing unit. The casing 12 is in general, of cylindrical or tubular form, one end 13 of the same being open, and the other end being closed there being 70 a block 14 integral with the end of the casing or supporting tube 12 to prevent the passage of liquids or fluids therethrough, except as hereinafter provided. The closed end is preferably provided with a plurality of ducts 75 or passageways 15 (see Figure 1 and Figure 5), these passageways being distributed about the axis of the casing in approximately parallel relation to said axis, and lying approximately in a circle concentric with the axis of 80 the casing.

Within the casing or tube 12, is positioned a rotatable member 20, having a cylindrical surface upon which is formed a plurality of spiral or helical grooves 21 extending from 85 one end of the member to the other. The outside diameter of the cylindrical member is approximately that of the interior of the cylindrical cavity within the casing, there being a sufficient clearance to permit free 90 100

rotation of the rotatable member within the casing, in accordance with the pressure exerted by the passage of fluids through the spiral grooves 21, above referred to.

5 Preferably the cylindrical member 20 is mounted for axial rotation upon a ball bearing 22, the same being mounted in recesses 23 and 24, the recess 23 being cut in the interior end of the block 14 at the end of the 70
10 casing, and the corresponding recess 24 being formed in the adjacent end of the cylindrical member 20. The block 14 is made preferably of brass, and the rotor member 20 of steel. The end of the cylindrical rotor 20 75
15 is positioned closely adjacent the block 14 and consequently, in rotation, intermittently obstructs the passageways, and prevents the free passage of liquids or other fluids through the same. At the discharge end of the cylindrical member 20 the raised helical portions intervening between the individual grooves 21 are provided with notches for the purpose of improving the self cleaning feature of the 80
20 nozzle and to enhance the operating qualities 25 of the nozzle generally.

The cylindrical member 20 is held in position within the tube and is prevented from substantial axial movement therein by means of a pin 30 which is transversely positioned 85
30 across the cavity within the casing 12, in apertures 31, and 32 formed in the casing wall. The pin is removable but is normally held in position in the casing wall at the end 90
35 of the rotatable member 20 by means of a coupling 33.

This coupling has screw-threaded engagement with the end of the casing in such manner as to enclose or encase that portion 100
40 of the casing or tube which contains the pin 30, and thus prevent removal of the pin, except subsequently to the removal of the coupling 33. The coupling 33 has screw-threads at one end whereby engagement is made with 105
45 a pipe line to a supply of fluid under pressure which is to be subjected to the atomizing process of the atomizer. The rotatable member 20, in relation to the pin 30 and the end block 14, is slightly movable in an axial direction, there being no necessity for a tight 110
50 fit as regards the end pivotal connection of the rotor, since the outflow of fluids through the tube 12 and through the spiral passage of the rotatable member 20, serves to force this member to the left, as shown in Figure 1 of the drawing, into close proximity with the 115
55 terminal block 14 in the end of the casing.

The apparatus, as herein above described, 120
60 forms a complete operative unit which may be utilized for atomizing hydro-carbon fuel, for example, in a furnace unit or similar fuel burning means. For many uses, however, it is desirable to add an additional member forming a separable nozzle 40, this nozzle being in screw-threaded engagement with a coupling member 41, which in turn has screw- 125
65

70 threaded engagement with the end of the block 14. The nozzle 40 is, because of the screw-threaded engagement with the coupling 41, removable and consequently it is possible to make use of a number of nozzles having ducts or passageways 42 of dissimilar cross section, and thus vary the volume of fluids ejected from the atomizer or the pressure of atomization.

75 The bore 44 of the nozzle coupling 41, is coaxially constructed in relation to the bore 45 which forms the connecting means to the casing 12 of the tube 10, and bore 45 is countersunk to form an annular ledge to seat the outer end of the block 14. By this construction also a chamber or cavity 46 is formed intermediate the end of the block 14, and the countersunk portion of the bore 45 which serves as a mixing chamber in which the incoming fluid, as it passes through the outlet ports of the various ducts 15 is thoroughly intermixed, and the particles further broken up after their passage through the current interrupting mechanism hereinabove described. After the mixing operation in the 80
85 chamber 46, the fluid passes out of the nozzle duct 42 into the interior of the furnace or other chamber to which the atomizer is applied.

Operation

90 The operation of the atomizer may be briefly indicated at this point. The fluid, such as for example, a hydrocarbon oil is connected under pressure to the coupling 33 100 and permitted to pass through the spiral grooves 21 formed on the surface of the rotatable member 20 within the interior of the atomizer casing 12. The movement of this fluid under pressure causes a rotation of the 105
110 rotor 20 in a direction dependent on the direction of the grooves, and consequently there is an intermittent valvular action in relation to the inlet ports of the various individual ducts 15 in the closed end of the casing. The starting and stopping of each fluid stream as 115
120 it passes from a given spiral groove into a given duct 15 is instantaneous due to the fact that each groove at the end is cut in an axial direction, to form a notch 21a, the rotating member thus presenting at the end thereof adjacent the inlet portion of the ducts, cutting edges formed by plane surfaces each lying approximately in a plane passing through the axis of the rotor. This intermittent making and breaking of the fluid currents passing through the various individual ducts, serves to break up the fluid here assumed to be a hydrocarbon, into a plurality of jets, and, inasmuch as the rotor rotates with a relatively rapid speed, a thorough breaking up of the liquid is secured. The atomizer, as described, may be successfully employed without the end nozzle for various purposes. The end nozzle with its single out- 125
130

let duct 42, secures a more thorough breaking up of the fluid in the mixing chamber 46 into which the intermittent jets of fluid are passed, becoming thoroughly intermixed therein. Should the volume of liquids or fluids passing out of the nozzle be too great, the nozzle may be readily removed and replaced by a new nozzle adapted to the specific requirement of the atomizer.

Attention should be directed to one or two features of my invention which are of considerable importance. In the first place, it should be reiterated that the steel rotor head in engagement with the brass head 14 insures a continuous connection between the two members, irrespective of the amount of wear which the device may receive. This is of considerable advantage in atomizers of the present type, inasmuch as the proximity of the rotor and the nozzle head insures a clear passageway for the fluid. It has been found that without this rotatable member, the passage ducts clog, and the whole device becomes inefficient or entirely inoperable.

Another feature is the utility with which the atomizer may be employed for fluid under diverse pressures. The atomizer has been successively used under a pressure of 200 pounds per square inch, and also at low pressures just sufficient to cause rotation of the rotor. A further important advantage of my invention resides in the ease in which the nozzles may be changed to accommodate changes in density or viscosity of the fluid. Spiral rotatable passageways are desirable, as it is easier in this way to atomize the fluid, and this atomization with such passageways tends to vary with the pressure changes; the rotor arrangement, furthermore, facilitates the use of ducts of small cross-section which are very desirable in pressure control.

It will be apparent to those skilled in the art that modifications of the invention herein shown and described may be made, and it is desired therefore to protect the invention broadly as well as specifically, as indicated by the claims hereto appended.

I claim:

1. A burner nozzle comprising a casing having a series of passageways at one end thereof and a cylindrical chamber therein communicating with the said passageways, a rotatable member in the said chamber having a series of inclined openings therein adapted to communicate with the said passageways, and so inclined and positioned that when a liquid-containing fuel is passed through the said openings the said member will be rotated, producing intermittent free communication of the said openings with the said passageways, and pulsation of the said fuel through said passageways.

2. A burner nozzle for fluids under pressure comprising a tube, a block at one end of

said tube having a plurality of passageways from the interior to the exterior of the tube, and a cylindrical rotatable member positioned within the tube and in close proximity to the passageways, adapted to intercept intermittently the movement of fluid through said passageways, said rotatable member being of a form so as to be rotated solely by the unrestricted passage of fluid through said tube in a direction parallel to the axis of the tube.

3. A burner nozzle for fluids under pressure consisting of a tube open at one end; a block positioned at the other end of the tube; a plurality of ducts in said block extending from the interior to the exterior of the tube; and a cylindrical rotatable member mounted within said tube, one end of said cylindrical member having radial portions positioned to form intermittent obstructions for the inner ends of the ducts when the said cylindrical member is rotated, said cylindrical member being of a form so as to be rotated solely by the passage of fluid through the tube.

4. A burner nozzle for fuel liquids under pressure consisting of a tube open at one end, a block positioned at the other end of the tube, a plurality of ducts in said block extending from the interior to the exterior of the tube, and a cylindrical rotatable member mounted within said tube, the sides of said member having formed thereon a plurality of spiral grooves extending from one end of the same to the other, said spiral grooves presenting at one end of the member radial portions positioned so as to form intermittent obstructions for the inner ends of the ducts when the cylindrical member is rotated.

5. In a burner nozzle the combination of a casing open at one end and having a block at the other end, said block having ducts positioned thereon and communicating from the interior of the casing to the exterior thereof, a rotatable cylindrical member positioned within the casing, said member having helical grooves formed on the surface thereof adapted to successively communicate with said ducts, said grooves at the end of the cylindrical member presenting therebetween end obstructions adjacent said block adapted to intermittently obstruct said ducts upon rotation of said member by the passage of fluid through the casing, means for preventing substantial axial movement of said cylinder, and a nozzle removably attached to said block and communicating with said ducts.

6. In a burner nozzle, the combination of a casing having a hollow interior open at one end; a plurality of ducts at the other end of said casing communicating from the interior of the casing to the exterior thereof; a nozzle removably attached to the end of the casing in which said ducts are positioned, there being formed a chamber intermediate the end

- of the casing and said nozzle for the mixing of fluids passing therethrough; a rotatable cylindrical member positioned within said casing, said member having spiral grooves formed thereon and terminating at one end of the member so as to form a plurality of radial notches adapted in rotation to intermittently permit free passage of liquid through said ducts; means for supporting said member so as to permit free rotation thereof; and means for preventing axial movement of said rotatable member.
7. In a burner nozzle, the combination of a tube closed at one end, and having a plurality of passageways in said closed end communicating from the exterior to the interior of the tube; a nozzle having a single passageway in communication with the end of the tube in which said passageways are formed;
- 15 20 25 30 35 40 45 50 55 60 65 70 75 80 85 90 95 100 105 110 115 120 125 130 135
- 20 a cylindrical member positioned within said tube and having a plurality of spiral grooves formed thereon whereby terminal radially extending notches are formed at the end of the cylinder adjacent the inner end of said passageways; a bearing intermediate the closed end of said tube and the adjacent end of said cylindrical member; said closed tube end and adjacent end of the cylindrical member having recesses formed therein to retain said bearing in position; and a pin positioned lengthwise across said tube at the other end of the cylindrical member to retain said member from substantial rearward movement.
8. In a burner nozzle, the combination of a tube closed at one end, and having a plurality of passageways in said closed end communicating from the exterior to the interior of the tube; a nozzle having a single passageway in communication with the end of the tube in which said passageways are formed; a cylindrical member positioned within said tube and having a plurality of spiral grooves formed thereon whereby terminal radially extending notches are formed at the end of the cylinder adjacent the inner end of said passageways; a bearing intermediate the closed end of said tube and the adjacent end of said cylindrical member, said closed tube end and adjacent end of the cylindrical member having recesses formed therein to retain said bearing in position; and a pin positioned lengthwise across said tube at the other end of the cylindrical member to retain said member from substantial rearward movement,
- 55 60 65 70 75 80 85 90 95 100 105 110 115 120 125 130 135
- 55 and means for retaining said pin in position, comprising a removable coupling member screw-threaded upon said tube and adapted in threaded position to prevent axial movement of said pin.
- 60 65 70 75 80 85 90 95 100 105 110 115 120 125 130 135
- 65 9. In a burner nozzle, the combination of a tube having an approximate cylindrical formation, and having one end open and a plurality of passageways formed in the other end of the tube transversely displaced about the tube axis and in communication with the in-
- terior of said tube; a cylindrical member within the tube having spiral grooves cut in the surface thereof; said grooves extending to one end of said member and forming a plurality of radially extending ridges and so positioned that upon rotation of the cylindrical member, they will intermittently obstruct communication from the spiral passageways of the cylindrical member to the passageways formed in the end of the tube; a bearing mounted in recesses formed in the ends of the cylindrical member and the closed tube end; and means for normally preventing substantial rearward movement of said cylindrical member, said cylindrical member being free to rotate about its axis within said tube.
10. In a burner nozzle, the combination of a tube having an approximate cylindrical formation, and having one end open and a plurality of passageways formed in the other end of the tube, transversely displaced about the tube axis and in communication with the interior of said tube; a cylindrical member within the tube having spiral grooves cut in the surface thereof; said grooves extending to one end of said member and forming a plurality of radially extending ridges adapted, on rotation of the cylindrical member, to intermittently obstruct communication from the spiral passageways of the cylindrical member to the passageways formed in the end of the tube; a bearing mounted in recesses formed in the ends of the cylindrical member and the closed tube end; means for normally preventing substantial rearward movement of said cylindrical member, said cylindrical member being free to rotate about its axis within said tube.
11. In a burner nozzle a tube having a plurality of passageways at one end, a cylindrical member rotatably mounted within the tube and having a plurality of raised portions forming spiral grooves therebetween, said cylindrical member being so positioned so that said grooves may intermittently communicate with the passageways formed in the end of the tube when said cylindrical member is rotated, the end of said raised portion adjacent the passageways forming intermittent obstructions to the passageways during rotation of said cylindrical member, and means for retaining said rotatable member in position in said casing.
12. In a burner nozzle the combination of a casing having a passageway in one end thereof, a rotatable element mounted on its surface and having spiral grooves thereon extending from end to end of said element, the outer diameter of said element being ap-

proximately equal to that of the inner diameter of the casing whereby a movable constricted passageway through the casing is provided by the spiral grooves on the rotatable element, and a member having a plurality of openings for the fluid disposed adjacent the discharge end of the casing, the end of said rotatable element being positioned in close relation to said member, said openings being positioned in the path of rotation of said spiral grooves.

13. In a burner nozzle the combination of a casing; a nozzle formed on one end of said casing providing a mixing chamber intermediate said nozzle and casing; a member having a plurality of openings disposed intermediate said mixing chamber and casing through which the fluid is discharged into said mixing chamber; a rotatable cylindrical element mounted within said casing, the diameter of said element being approximately that of the inner diameter of said casing, said rotatable element having a spiral groove formed in the surface thereof intermediate its ends whereby movement of the fluid along said spiral groove causes rotation of said rotatable element, and the openings in said member being in the path of the rotation of the discharge end of said groove whereby free flow of the fluid through said opening is intermittently obstructed by the rotation of said element.

14. In a burner nozzle, the combination of a cylindrical tube having a jet orifice at one end; a cylindrical element rotatably mounted within said tube having a tangential groove cut in the surface of said rotatable element intermediate its ends and inclined to the axis of said rotatable element, whereby a movement of fluids through said casing causes rotation of said rotatable element and an intervening member disposed between the jet and the cylindrical element provided with a plurality of openings for the purpose of establishing communication between the jet and the grooves in the cylindrical element, said openings being adjacent the end of said tangential groove whereby the free path of fluid through said opening is intermittently obstructed.

15. In a burner nozzle, the combination of means for supplying a fluid under pressure, a member having at least one aperture through which the compressed fluid is caused to discharge, and an element adapted to be rotated including means in close relation with the apertured member and on the pressure side thereof and adapted to intermittently obstruct said aperture, and said rotatable element also including means for causing rotation of the element when fluid under pressure passes through an aperture in said member.

16. In a burner nozzle the combination of a casing open at one end and having a block at the other end, said block having ducts posi-

tioned thereon and communicating from the interior of the casing to the exterior thereof, a rotatable cylindrical member positioned within the casing, said member having helical grooves formed on the surface thereon adapted to successively communicate with said ducts, said grooves at the end of the cylindrical member presenting therebetween end obstructions adjacent said block adapted to intermittently obstruct said ducts upon rotation of said member by the passage of fluid through the casing, and means for preventing substantial axial movement of said cylindrical member.

17. In a burner nozzle, the combination of a casing having a hollow interior open at one end, a plurality of ducts at the other end of said casing communicating from the interior of the casing to the exterior thereof, a rotatable cylindrical member positioned within said casing, said member having spiral grooves formed thereon and terminating at one end of the member so as to form a plurality of radial notches adapted upon rotation to intermittently permit free passage of liquid through said ducts, means for supporting said member so as to permit free rotation thereof, and means for preventing axial movement of said rotatable member.

18. In a burner nozzle, the combination of a tube closed at one end, and having a plurality of passageways in said closed end communicating from the exterior to the interior of the tube, a cylindrical member positioned within said tube and having a plurality of spiral grooves formed thereon whereby terminal radially extending notches are formed at the end of the cylinder adjacent the inner end of said passageways and which intermittently obstruct said passageways when said cylindrical member is rotated, a bearing intermediate the closed end of said tube and the adjacent end of said cylindrical member, said closed tube end and adjacent end of the cylindrical member having recesses formed therein to retain said bearing in position, and a pin positioned lengthwise across said tube at the other end of the cylindrical member to retain said member from substantial rearward movement.

19. In a burner nozzle, the combination of a tube having an approximate cylindrical formation, and having one end open and a plurality of passageways formed in the other end of the tube transversely displaced about the tube axis and in communication with the interior of said tube, a cylindrical member within the tube having spiral grooves cut in the surface thereof, said grooves extending to one end of said member and forming a plurality of radially extending ridges adapted on rotation of the cylindrical member to intermittently obstruct communication from the spiral passageways of the cylindrical member to the passageways formed in the

end of the tube, a bearing mounted in recesses formed in the ends of the cylindrical member and the closed tube end, and means for normally preventing substantial rearward movement of said cylindrical member, said cylindrical member being free to rotate about its axis within said tube.

5 In testimony whereof, I affix my signature.
